(57) **CLAIM**

The ornamental design for a watch clasp, as shown and described.

DESCRIPTION

FIG. 1 is a front-left perspective view of a first embodiment of the watch clasp;

FIG. 2 is a rear-left perspective view thereof;

FIG. 3 is rear-right perspective thereof;

FIG. 4 is a front-right perspective view thereof;

FIG. 5 is a top view thereof;

FIG. 6 is a bottom view thereof;

FIG. 7 is a right side view thereof;

FIG. 8 is a left side view thereof;

FIG. 9 is a front view thereof;

FIG. 10 is a rear view thereof;

FIG. 11 is a view showing the watch clasp in-use in an open position;

FIG. 12 is a view showing the watch clasp in-use in a closed position;

FIG. 13 is a front-left perspective view of a second embodiment of the watch clasp;

FIG. 14 is a rear-left perspective view thereof;

FIG. 15 is rear-right perspective thereof;

FIG. 16 is a front-right perspective view thereof;

FIG. 17 is a top view thereof;

FIG. 18 is a bottom view thereof;

FIG. 19 is a right side view thereof;

FIG. 20 is a left side view thereof;

FIG. 21 is a front view thereof;

FIG. 22 is a rear view thereof;

FIG. 23 is a view showing the watch clasp in-use in an open position; and,

(Continued)

FIG. 24 is a view showing the watch clasp in-use in a closed position.

The features shown in broken lines show environment only and do not form part of the claimed design.
